(57) CLAIM

The ornamental design for a food cover, as shown and described.

DESCRIPTION

FIG. 1 is a front perspective view of the food cover showing my new design.

FIG. 2 is a front elevation view thereof;

FIG. 3 is a rear elevation view thereof;

FIG. 4 is a left side elevation view thereof, the right side elevation view being a mirror image thereof;

FIG. 5 is a top plan view thereof; and,

FIG. 6 is a bottom plan view thereof.

The dot dash dot broken line in FIG. 6 depicts the boundary of the claim and forms no part thereof. The evenly spaced broken lines in FIG. 6 depict portions of the food cover that form no part of the claimed design.

1 Claim, 6 Drawing Sheets
